UNITED STATES PATENT OFFICE.

MOSES M. MARCUSE, OF NEW YORK, N. Y., ASSIGNOR TO WEST DISINFECTING COMPANY, A CORPORATION OF NEW YORK.

DESIGN FOR A CASING FOR SOAP-DISTRIBUTERS.

47,366.

Specification for Design.

Patented May 18, 1915.

Application filed March 10, 1913. Serial No. 753,433. Term of patent 14 years.

To all whom it may concern:

Be it known that I, MOSES M. MARCUSE, a citizen of the United States, residing in the city, county, and State of New York, have invented a new, original, and ornamental Design for a Casing for Soap-Distributors, of which the following is a specification, reference being had to the accompanying drawing.

The invention has reference to ornamental containers for liquid soap, generally placed upon a pivotal mounting conveniently for use in washing.

This casing is shown in Figure 1 of the drawing in an inclined position and in side elevation and in Fig. 2 the same is shown in a polar view.

Copies of this patent may be obtained for five cents each, by addressing the "Commissioner of Patents, Washington, D. C."

The design consists in giving the container a general form which is substantially globular, and so shaping the surface thereof, that it presents Doric or concave flutings extending from pole to pole, and widening from each pole to the circumference; said flutings being set side by side around the circumference.

What I claim is—

The ornamental design for a casing for soap distributors, substantially as shown and described.

MOSES M. MARCUSE.
